United States Patent Office

Des. 218,341
Patented Aug. 11, 1970

218,341

CUT AND DRY FLOWER HOLDER

Vincent Giannotti, Jr., Lexington, Ky.
(7214 Running Rope, Austin, Tex. 78731)

Filed May 13, 1969, Ser. No. 17,137

Term of patent 14 years

Int. Cl. D11—02

U.S. Cl. D35—3

FIG. 1

FIG. 2

FIG. 3

FIG. 4

FIG. 1 is a perspective view of the cut and dry flower holder of the new design.

FIG. 2 is a top plan view thereof.

FIG. 3 is a bottom plan view thereof.

FIG. 4 is a side elevational view thereof.

I claim:

The ornamental design for a cut and dry flower holder, substantially as shown and described.
